UNITED STATES PATENT OFFICE.

ERIK AUGUST FORSBERG, OF STOCKHOLM, SWEDEN, ASSIGNOR TO THE DE LAVAL SEPARATOR COMPANY, OF NEW YORK, N. Y., A CORPORATION OF NEW JERSEY.

MILKING-MACHINE PULSATORE.

Application filed August 30, 1927, Serial No. 216,360, and in Sweden September 17, 1926.

In milking machine pulsators from which pneumatic pulsations are transmitted toward the teats, it is known to control the element from which these pulsations emanate by an oscillating fly-wheel mass, which is suitably connected with a regulating spring in order to obtain the desired time of oscillation. This fly-wheel mass reverses said element at certain regular intervals.

10 Pulsators of this kind have not gone into general use because of certain serious defects. In earlier known constructions the driving mechanism has been so connected with the oscillating fly-wheel mass that energy has been transmitted to the fly-wheel mass near to the point of reversal of direction of oscillation. In such constructions, variations in the driving mechanism are likely to influence the fly-wheel mass in such a way as to 20 vary the time of oscillation.

In certain earlier constructions, the regulating element is so directly connected with the oscillating fly-wheel mass that a certain position of the former always corresponds to 25 a certain position of the latter. Such a construction has the defect that the amplitude of the oscillation must be kept small and the influence of the driving mechanism on the time of oscillation is increased.

30 An application filed May 28, 1927, by J. V. Erling, Serial No. 194,911, comprises a pulsator of the above generic type, but embodies structural features that eliminate certain defects therein. The invention is characterized by the fact that the fly-wheel mass and the regulating element are not fixedly connected but are so coupled together that the amplitude of the fly-wheel mass is 35 independent of the movement of the regulating element. Another feature of the invention is that the driving mechanism is of such a nature, and so connected with the fly-wheel mass, that the driving power is transmitted from the driving mechanism to the fly-wheel 40 mass only during a part, and a limited part, of the oscillating movement, whereby the fly-wheel mass near to the points of reversal will be entirely independent of the driving mechanism.

45 The present invention comprises an improvement on the said Erling pulsator and involves, or at least permits, a simplification of construction whereby the pulsator unit may comprise merely a fly-wheel mass and

a pneumatically operated piston, each controlling the movement of the other, the piston operating in a cylinder and controlling air ports through which pneumatic pulsations are transmitted to a secondary pulsator which directly transmits pulsations to 55 the teat cups. In the preferred embodiment, the primary pulsator is adapted to maintain, in the line leading to the secondary pulsator, for the greater part of the time, relatively 60 low absolute pressure (conveniently a partial vacuum) interrupted at regular intervals by short puffs of air at a relatively high absolute pressure (preferably air at atmospheric pressure). The invention comprises a number of other features which are fully explained in the description that follows.

55 Embodiments of the invention are shown in the accompanying drawings, wherein—

Fig. 1 is a longitudinal sectional view through a pulsator embodying my invention.

Fig. 2 is a section on the line 2—2 of Fig. 1, looking in the direction of the arrows.

Fig. 3 is a longitudinal sectional view of a modified construction of pulsator.

Fig. 4 is a section on the line 3—3 of Fig. 3.

Fig. 5 is a detail sectional view of a modified form of cylinder and piston.

A cylinder *a*, containing a piston *b*, is provided with ports *c*, communicating with a source of pressure—most conveniently the atmosphere. It is preferred to insert a strainer *d* to exclude coarse impurities in the air. The cylinder is also provided with ports *e* communicating with the interior of the pulsator housing *x*. The housing, through the connection *f*, communicates with a vacuum line that connects with a vacuum pump (not shown). The interior of the housing is, therefore, under a constant vacuum. The inner end of cylinder *a* is open to the interior of the housing. The outer end of the cylinder communicates with a connection *g* leading to the secondary pulsator, which transmits pulsations direct 95 to the teat cup. This secondary pulsator may be of any approved type, as, for example, that shown in the Leitch Patent No. 1,255,186, dated February 5, 1918.

Piston *b* is provided with ports *h* which, 100 as the piston approaches one end position (on the drawing the lower), communicate with the cylinder ports *c*, and which, as the

piston approaches the other end position (the upper), communicate with the cylinder ports *e*.

The cylindrical wall of cylinder *a* is flanged at its upper end to provide a stop *i* which limits the upward movement of the piston. Piston *b* engages with a connecting rod *j* which at its other end is connected with the crank *k*. The rod *j* is, however, not secured to the piston *b*, but only abuts against the same and is free to follow the crank *k* in a movement greater than that corresponding to the movement of the piston up to the stop *i*. To secure the right engagement between the piston *b* and the rod *j*, the lower end of the latter may carry a loop *m'* slideable, with sufficient play, along a guide rod *m* secured to an interior projection on the housing.

Crank *k* may be connected, in any suitable manner, with the fly-wheel mass *p*, which is actuatable by a suitable tension device so that it will swing just like the balance in a watch. In order to concentrate a big, effective fly-wheel mass within a small space, it is preferred not to connect crank *k* directly therewith, but to suitably gear the same thereto. In the drawing, crank *k* is connected with the shaft of a large gear wheel *n* which engages with a small gear wheel, or pinion, *o*, on the hub of the fly-wheel mass *p*, which turns on a shaft *q* secured to the housing. The latter is acted upon by a spiral spring *r*, the inner end of which is secured to the fly-wheel mass and the outer end of which is secured to an arm fixed in the housing.

The fly-wheel mass *p* is suitably provided with wings *s*, the fan action of which damps the oscillating movement of the mass.

The operation is as follows:

Assume that at the beginning piston *b* is in its lowest position, and that crank *k* is likewise in its lowest position so that rod *j* touches, or, at least, is in immediate proximity to, the bottom of the piston. As the spring *r* should, of course, reach its tension-free position at the same moment as the piston reaches its lowest point, the starting position mentioned above is to be considered as the natural one. The spring, in other words, has a tendency to turn the balance and the parts connected with it towards this position, besides which piston *b*, if the parts are arranged as shown on the drawing, will sink down to its lowest position under the influence of the force of gravity.

If, through tube connection *f*, the interior of the housing is connected with a source of vacuum, it very rapidly becomes evacuated and the pressure above the piston is reduced. The lower end of the piston being under atmospheric pressure, the piston begins to move upwards. When the movement has proceeded so far that port *h* passes beyond

ports *c*, communication between the under side of the piston and the atmosphere ceases; there being no connection to the atmosphere through *g*, which, as hereinbefore stated, leads to a secondary pulsator of suitable construction. However, air fills the space below the piston and in the line to the secondary pulsator and this space is so little enlarged by the completion of the upward movement of the piston that the air confined in such space suffices, with little expansion, to continue to drive the piston upward against vacuum. As the piston approaches its limit of upward movement, ports *h* get into communication with ports *e*, and the air below the piston flows into the interior of the housing and escapes through the connection *f* into the vacuum line. The force acting on the piston now ceases and the movement of the piston rapidly slows down, being finally limited by the stop *i*. The crank *k* has, however, received an impulse of upward movement, which transmitted to the balance, starts its movement of oscillation in one direction. Owing to the free connection between piston *b* and crank *k*, the balance continues its movement under the influence of the received impulse. The oscillation thus assumes the character of the oscillation of a pendulum.

In the tube connection *g* and in the line leading therefrom to the secondary pulsator, vacuum now prevails. When the balance has transmitted the received energy of motion to spring *r*, it proceeds, under the influence of the spring tension, on its reverse oscillating movement. When the balance has come sufficiently near its middle position, crank *k* and piston *b* again engage. The piston *b* is pressed down towards its lowest position, whereby ports *c* and *h* again come into communication. Air at atmospheric pressure now flows in under the piston and fills the space thereunder as well and in the line to the secondary pulsator. By means of the motion-energy of the balance, it continues its reverse oscillation until the piston is pushed down to the bottom of the cylinder. The balance continues its movement in the reverse direction. The procedure previously described is now repeated. The piston pushes the rod and the crank upwards and the balance receives sufficient energy to continue its oscillating movement.

A difficulty that is encountered is to prevent the oscillations of the balance from getting too great. In order that the mechanism shall work safely and independently of temporary movement-resistances, impurities, etc., there must be surplus of motion-energy; that is, the quantity of energy developed by the piston must be greater than what is required to overcome the normal frictional resistance. To this end, the balance is, as mentioned, provided with the

fan-acting wings *s*. If the impulses of motion are particularly strong, the amplitude of the balance will be great and its average speed high, a considerable quantity of energy being consumed by the fly effect of the wings. If, on the contrary, the impulses of motion are feeble, the amplitude of the balance and its average speed will be reduced and the energy consumption will therefore be smaller. This difference in energy consumption between great and small amplitudes can be made quite considerable and corresponds thus to a great allowable difference in the energy developed in one stroke. The frequency of the oscillations is, according to well known principles for damped oscillations, independent of the amplitude of the oscillation, wherefore even a rather great difference in motion resistance cannot influence the frequency of the oscillations.

As long as the upper face of the piston is under vacuum, the course of movement will be as described above. Each time the balance passes its middle position and the piston thus is pressed down against the bottom of the cylinder, air at atmospheric pressure is admitted under the piston and in the line to the secondary pulsator. As soon as the middle position is passed and the piston has moved a little from its extreme position, the communication with the atmosphere is interrupted and the space under the piston and in the line to the secondary pulsator is brought under vacuum. The result is that the line to the secondary pulsator vacuum is under vacuum the greater part of the time, but that, in each oscillation back and forth of the balance, air at atmospheric pressure is, for a relatively short time, admitted to said line. There will thus prevail vacuum interrupted at regular intervals by air puffs of high pressure. These air puffs can be used to regulate the movement of the secondary pulsator.

The mechanism described may be modified in detail. Thus, piston *b* and crank *k* may be connected in any way that allows the crank to continue swinging after the movement of the rod has ceased. For example, the rod may be secured in fixed relation to the piston and may be movably attached to the crank as by a fork. It is also permissible, although it has been found not to be necessary, to facilitate the assumption by the mechanism of a starting position by arranging a spring tending to convey the piston toward its lowest position; or the crank may be provided with an overweight tending to direct the piston downward; or the piston or cylinder may be so magnetized as to tend to hold the piston in its lowest position.

The machine above described is, in fact, only one example of different possible em-

bodiments of the invention. In Figs. 3 and 4 another embodiment is shown, which may in practice have certain advantages. Here the rod *j* is missing and instead the crank acts directly on the piston. To reduce the friction, a ball bearing is inserted, rolling over the upper surface of the piston. In this embodiment, the balance is shown directly connected with the crank, or, rather, the crank pivot is fixed directly on the balance, although gearing, such, for example, as shown in Figs. 1 and 2, may be interposed between the crank and the balance.

In Figs. 3 and 4, *a'* is the cylinder, *b'* the piston, *c'* the cylinder ports connecting with atmosphere, *e'* the cylinder ports connecting with the interior of the housing, *f'* the connection to vacuum, *g'* the connection to the secondary pulsator, *h'* the piston ports, *t* the crank pin fixed directly on the fly-wheel mass *p*, *r'* the spring, *u* a ball bearing roller engaging the end of piston *b'*, and *v* a ball bearing roller on a shaft *g'* secured to the housing and within the hub of the fly-wheel mass.

In Fig. 5 there is shown a somewhat modified arrangement of the cylinder and the piston. The cylinder *a''* is by means of a cover *y* shut off from the interior of the pulsator housing, which thus need not be put under vacuum. The vacuum line *f''* is instead coupled direct to the upper part of the cylinder *a''*. Ports *c''* and *h''* correspond to ports *c* and *h* of Figs. 1 and 2. The recess *e''* in the cylinder wall takes the place of port *e* of Figs. 1 and 2.

This modification shown in Fig. 5 has the advantage that the balance can work under full atmospheric pressure, the necessary damping thereby being more easily obtained.

It should be understood that word "cylinder" is used in its technical, and not in its mathematical, sense. Though, in practice, a cylindrical shape is preferred, an equivalent member of any shape may be used. Thus, for example, the "cylinder" may have the shape of a circle section, in which a radial piston is oscillating to and fro, as in the application filed May 28, 1927, by S. J. Erling, Serial No. 194,911. In fact, any arrangement by means of which atmospheric pressure and vacuum, or any equivalent relatively high and low absolute pressures are, in the way mentioned in the description, alternately admitted to a chamber, limited in some way or other by a movable wall, would be an equivalent of the specific construction herein disclosed.

As pointed out above, the arrangement of the pulsator is preferably such that it should automatically start as soon as it is connected with vacuum. It may, however, be possible, with some embodiments of my invention, especially if vacuum is let on

particularly slowly, that the first impulse will not become sufficiently strong to start the pulsator. In order to make possible, in such case, the starting of the pulsator, it 5 may be advisable to provide the pulsator with a special starting device. A simple device for this purpose may comprise a metal rod extending through a hole in the outer wall of the pulsator, the rod being, on the outside 10 of the housing, provided with a push button and pressed outwards by means of a spring. The inner end of this rod, on being pushed in, will strike against a nose on the crank, the crank thereby being moved aside 15 so that a sufficient impulse of motion is obtained. When releasing the button, the rod will return to its original position and give free passage for the crank to swing in a normal way.

20 Having now fully described my invention, what I claim and desire to protect by Letters Patent is:

1. A milking machine pulsator comprising a low pressure air line, an air pulsation line, a cylinder, a piston therein providing at one side thereof a chamber in communication with the pulsation line, the other side of the piston being in communication with the low pressure line, there being ports in 25 the cylinder communicating respectively with the low pressure line and with a source of relatively high pressure and a port in the piston adapted to connect said chamber alternately with high pressure and low pressure, an oscillatory fly-wheel mass, and motion transmission means between the piston and fly-wheel mass adapted, in the movement of the piston from the position at which 30 said chamber is under high pressure to the position at which said chamber is under low pressure, to transmit an impulse of motion to the fly-wheel mass.

2. A milking machine pulsator comprising a low pressure air line, a pulsation air line, a cylinder, a piston therein one side 45 of which is in communication with the low pressure line and the other side of which is in communication with the pulsation line, ports adapted in different positions of the piston to connect the pulsation line respectively with the low-pressure air line and with air at relatively high pressure, a spring-actuated oscillatory fly-wheel mass, means by which the movement of the piston in one direction 50 is transmitted to the fly-wheel mass to positively move it in one direction and by which the fly-wheel mass in its reverse movement positively reverses the piston, the fly-wheel mass being movable under its own momentum substantially beyond the points to which it is moved by and moves the piston.

3. A milking machine pulsator comprising a cylinder, a piston, a low pressure line 55 communicating with the space at one side of the piston, an air pulsation line communi-

cating with the space at the other side of the piston, a spring-actuated oscillatory fly-wheel mass, movement transmission means between the piston and the fly-wheel mass by means of which each positively actuates 70 the other, the fly-wheel mass being movable in one direction under its own momentum substantially beyond the point to which it is moved by said piston and transmission means and adapted to actuate said transmission means to reverse the piston after the fly-wheel mass has completed a substantial 75 part of its movement of reversal, means by which the piston, in its movement to actuate the fly-wheel mass, is arrested before the 80 movement of the fly-wheel mass is completed, and ports adapted in opposite positions of the piston to connect the space communicating with said pulsation line respectively with the low pressure line and with a source of 85 higher pressure, the ports being so arranged that the pulsation line is under low pressure during the greater part of the time and is under high pressure at regular and relatively short intervals.

4. A pulsator for milking machines which comprises a low pressure line, an air pulsation line, a cylinder, a piston therein adapted in one position to connect the pulsation line with a source of higher pressure and in another position to connect the pulsation line with the low pressure line, said piston being pneumatically operable from one position to the other, an oscillatory fly-wheel mass, and motion transmitting means between the fly-wheel mass and piston adapted to transmit the motion of the piston, when so pneumatically actuated, to the fly-wheel mass to oscillate it in one direction and to transmit the reverse motion of the fly-wheel mass to the 100 piston to reverse it.

5. A pulsator for milking machine which comprises a low pressure line, an air pulsation line, a cylinder, a piston therein adapted in one position to connect the pulsation line with a source of higher pressure and in another position to connect the pulsation line with the low pressure line, said piston being pneumatically operable from one position to the other, and a loose connection between the fly-wheel mass and piston adapted to cause the piston, when so pneumatically actuated, to move the fly-wheel mass in one direction and adapted to cause the fly-wheel mass in its opposite movement to reverse the piston 110 and adapted to allow the fly-wheel mass to move independently of the piston except during an approximately middle part of its movement in each direction.

6. A pulsator in accordance with claim 4 125 in which the motion transmitting means between the piston and the fly-wheel mass is loose so that said elements act on each other only within a relatively small space near the middle position of the fly-wheel mass.

whereby the time of oscillation may be substantially independent of the strength of the motion impulse.

7. A pulsator in accordance with claim 4 in which the fly-wheel mass comprises wings 5 acting as a fan to damp the movement of the fly-wheel mass and thereby limit its amplitude.

8. A milking machine pulsator comprising 10 a low pressure air line, a pulsation air line, a cylinder, a piston therein one side of which is in communication with the low pressure line and the other side of which is in communication with the pulsation line, 15 there being ports in the piston and cylinder adapted in different positions of the piston to connect the pulsation line respectively with the low pressure line and with air at relatively high pressure, an oscillatory fly- 20 wheel mass, and motion transmission means between the piston and fly-wheel mass adapted, in the movement of the piston from the position at which said chamber is under high pressure to the position at which said 25 chamber is under low pressure, to transmit an impulse of motion to the fly-wheel mass.

9. A milking machine pulsator comprising a cylinder, a piston, a low pressure line com-

municating with the space at one side of the piston, an air pulsation line communicating 30 with the space at the other side of the piston, an oscillatory fly-wheel mass, movement transmission means between the piston and the fly-wheel mass by means of which each 35 positively actuates the other, the fly-wheel mass being movable in one direction under its own momentum substantially beyond the point to which it is moved by said piston and transmission means and adapted to actuate said transmission means to reverse the 40 piston after the fly-wheel mass has completed a substantial part of its movement of reversal, means by which the piston, in its movement to actuate the fly-wheel mass, is arrested before the movement of the fly- 45 wheel mass is completed, and ports adapted in opposite positions of the piston to connect the space communicating with said pulsation line respectively with the low pressure line and with a source of higher pressure. 50

In testimony of which invention, I have hereunto set my hand, at Stockholm, Sweden, on this 12th day of August, 1927.

ERIK AUGUST FORSBERG.
